UNITED STATES PATENT OFFICE.

JAMES DROHAN, OF NORTH PACIFIC JUNCTION, MINNESOTA.

DESIGN FOR A BOB-SLEIGH KNEE.

SPECIFICATION forming part of Design No. 14,163, dated August 14, 1883.

Application filed June 20, 1883. Term of patent 7 years.

To all whom it may concern:

Be it known that I, JAMES DROHAN, of North Pacific Junction, in the county of Carlton and State of Minnesota, have invented a new and Improved Design for a Bob-Sleigh Knee, of which the following is a full, clear, and exact description.

This invention relates to a design for a bob-sleigh iron or knee; and it consists in the configuration of said iron, as shown in the accompanying drawings.

Reference is to be had to the accompanying drawings, forming a part of this specification, in which similar letters of reference indicate corresponding parts in all the figures.

Figure 1 of drawings is a view in perspective, as seen from the under side of my new design for a bob-sleigh knee; and Fig. 2 is an inverted plan view of the same.

The bob-sleigh iron A, of novel configuration, consists of a plate which is plain or flat on its top *b*, but has a longitudinal groove, *c*, on its under side, *d*. The upper marginal configuration is partly circular, being bounded on its sides by opposite convex edges *e e*, united by marginal front and back portions, *f f*, which are straight and parallel with one another, and which cross the opposite ends of the groove *c*. The plate-shaped bob-sleigh iron

or knee thus presents an upper facial configuration of a circle mutilated by the removal of opposite segmental portions, and it further presents on its opposite side portions beveled or sloping surfaces *g g*, which converge toward one another in a downward direction, and are made to vanish at opposite ends, where they meet the ends of the side margins of the grooves *c*, thus doing away with all abruptness, and giving a slight and neat or spring-like finish to the "irons" as viewed from the side.

Having thus described my invention, I claim as new and desire to secure by Letters Patent—

The within-described design for a bob-sleigh iron or knee, the same being of plate-like form, flat on its upper surface, but grooved on its under side, and presenting an upper facial configuration of mutilated circular form, having convex sides, but straight and parallel front and back margins or portions, and having its convex side portions made to present beveled surfaces converging toward one another in a downward direction and vanishing at opposite ends, as shown.

JAMES DROHAN.
